JOHN SCHUMACHER AND JOSEPH E. SCHUMACHER, OF LOS ANGELES, CALIFORNIA.

FEEDING AND SEVERING APPARATUS.

1,197,553.

Specification of Letters Patent.

Patented Sept. 5, 1916.

Application filed April 29, 1916. Serial No. 94,468.

To all whom it may concern:

Be it known that we, JOHN SCHUMACHER and JOSEPH E. SCHUMACHER, both citizens of the United States, residing at Los Angeles, in the county of Los Angeles and State of California, have jointly invented new and useful Improvements in Feeding and Severing Apparatus, of which the following is a specification.

10 This invention relates to feeding and severing apparatus, or apparatus in which a product is formed or treated upon the continuous supply of the component parts or substances thereof, or of materials or substances for treating other materials or substances likewise supplied or fed and severed.

More particularly the apparatus is adapted for the manufacture of plaster-board and similar substances, for which purpose one or more sheets of paper or the like is or are fed continuously from a roll or rolls of the same, a plastic or like material being deposited upon or between such sheets, the resultant product in finished or partly finished form and condition being subdivided into predetermined lengths or into units of predetermined size and shape.

A particular feature of the present invention consists of means for so subdividing the product as it is continuously formed, or treated and advanced, whereby such product may be so subdivided in the advance or movement thereof, and without interference with the means for causing such advance or necessitating cessation of the movement thereof. Apparatus of this general character is disclosed in another application for United States Letters Patent filed by us jointly April 23rd, 1915, Serial No. 23,521, for apparatus for making plaster board and the like, and similar apparatus is disclosed in United States Letters Patent No. 1,176,322, issued jointly to us March 21st, 1916, for process of making plaster board and the like.

The invention has for particular objects the provision of apparatus or mechanism generally organized and characterized as above set forth, and which will be superior in point of relative simplicity and relative inexpensiveness of construction and formation, convenience and positiveness and efficiency in service and durability, and which will be generally superior in efficiency and

adaptability for varying kinds and conditions of service.

With the above and other objects in view, the invention consists in the novel and useful provision, formation, construction, combination, association and relative arrangement and mode of application of parts, members and features, all as hereinafter described, shown in the drawing and finally pointed out in claims.

In the drawing: Figure 1 is an isometric view, broken away for fullness of illustration, of mechanism or apparatus organized in accordance with and for the practice of the invention, and specifically devised for the purpose of building up or forming a product comprising strips or sheets of paper or other flexible material and an interposed body of plastic or other material, in accordance with the general constitution of plaster-board as made by the apparatus and following the process of our other said application and our said issued Letters Patent; and, Fig. 2 is an isometric view of a cutter shown in operative position in Fig. 1, the same being shown in Fig. 2 in detached position, and constituting an important feature of the improvements constituting the present invention.

Corresponding parts in both figures are designated by the same reference characters.

Referring with particularity to the drawing, it will be understood that the apparatus or mechanism shown therein is only one form or embodiment of the invention, being shown as adapted to produce separate plaster-board units A, having each an upper paper or similar surface member 3, a lower paper or similar surface member 4 and an interposed body 5 of plastic or other material. Such units, shown stacked upon a table B in Fig. 1, are therein indicated as in process of formation, the upper surface member 3 of each unit A being produced from a continuously fed sheet of paper 6 supplied from a roller 7, the lower surface member 4 of each such unit A being shown as produced from a continuously fed sheet 8 of paper fed from a roller 9, and the body portion of each such unit A being shown as produced from suitable plastic material 10 fed downwardly upon the continuously fed sheet 8 from a hopper 11. The sheet 8 is

shown as fed from the roller 9 onto an endless belt conveyer 12 operated by and trained about horizontal spaced rollers 13 journaled at their ends as at 14 in a suitable horizontal frame 15. The roller 7 is supported above the endless belt conveyer 12 by an upright frame member 16 which likewise is branched out to support the hopper 11, and furthermore supports a loosely journaled compression roller 17 which bears downwardly upon the paper sheet 6 drawn from the roller 7 to compress between such sheet 6 and the lower sheet 8 the plastic material 10 which is sandwiched between such 15 sheets, as clearly shown in Fig. 1. The frame member 16 likewise carries suitable side-boards or retaining walls 18 rising above the upper course of the belt conveyer 12 and confining the zone within which the 20 plastic material 10 is fed to the lower paper sheet 8 and between the said sheet and the sheet 6, so as to prevent escape of the plastic material from such sheets, and to retain it effectively for disposition between such 25 sheets.

C designates a cutter shown in working position in Fig. 1 and in detached position in Fig. 2, such cutter being used for successively severing the plaster-board units A 30 from the stock consisting of the advancing upper and lower sheets 6 and 8 and the interposed plastic material. Such cutter is utilized during the movement of such stock which is designated D, and is applied to the 35 conveyer 12 and the upper course thereof during the movement thereof, being passed between such upper course of the conveyer and the stock D, the severing action taking place while the stock and conveyer are moving in the direction of the arrow in Fig. 1. In order to obtain units A which, with the standard width predetermined in accordance with the width of the sheets 6 and 8, which have predetermined lengths, a suitable 40 measuring stick or rule c is utilized, the same being placed upon the advancing stock D with one end even with the advancing end of the stock. This rule being of the proper length required for each unit, or for 45 the next unit A, the cutter C is slipped between the upper course of the conveyer and the stock D at the other end of the ruler or measuring stick, and is operated to sever the unit beneath the measuring stick from 50 the stock during the movement of the stock upon the conveyer. Thus, there is no halt in the procedure of forming and feeding the stock incident to subdividing it, the severed unit being lifted by the operator or operators 55 and placed upon the stack upon the table B, the ruler having first been lifted and thrown back onto the advancing end of the stock next adjacent to the severed unit, for the purpose of measuring off the next 60 succeeding unit to be severed.

The cutter C comprises an elongated frame or body 19 provided at one end with a hand-grasp or handle 20, and at the other end with a nose or point 21 slightly back of the terminal portion of which, as at 22, 70 is attached one end of a cutting wire, cord or the like 23, of substantially the same length as the body 19, and the other or free end of which is provided with a handle or hand-grasp 24 adapted to lie flat upon the 75 handle 20, with the cutting wire or cord 23 substantially flat upon the body portion 19, with the parts in the last mentioned positions or relations, the handles 20 and 24 may be grasped in one or both hands and 80 the nose 21 passed beneath the stock D and above the upper course of the conveyer 12 at the following or rearward end of the roller or gage stick c, the nose 21 readily making a passage for itself beneath the 85 stock and traversing the smooth belt conveyer. When such traverse has been completed, so that the cutter lies entirely transverse of and beneath the stock, the handle 20 is grasped by the operator in one hand, 90 and the handle 24 in the other hand, such latter handle being raised and the cutter wire 23 meanwhile put under strain or pulled upon, whereupon, as clearly indicated in Fig. 1, the cutter wire is caused to cut and 95 sever the stock D transversely at the following end of the gage stick c to sever a unit A beneath such gage stick from the remainder of the stock. This operation is performed while the stock is moving upon 100 the conveyer, the operator moving along beside the conveyer and advancing stock. When the severance is completed the measuring gage c is, as stated, placed back upon the advancing fresh end of the stock, the 105 severed unit is deposited upon the table B, and the operator then proceeds to sever the next succeeding unit A from the stock in the same manner, and so on indefinitely.

The use of the cutter disclosed, in the 110 manner set forth, namely, during the advance of the stock, obviates any necessity of halting such advance to produce the severance of each unit, as would otherwise be necessary to produce a clean unmutilating cut, in the use of a cutter having a fixed position of service. Furthermore, the cutter operating in an upward direction, the belt conveyer is saved from any mutilation or injury which would be likely to occur upon the down stroke of any cutter acting upon the stock, and particularly were any cutter element employed other than the wire or cord or the like 23, which latter, in accordance with the invention, is at all times isolated from the conveyer by the relatively broad cutter body 19. The use of such a cutter permits of speedy and continuous operation of the machine or apparatus, together with accurate severance of the units 115 120 125 130

from the advanced stock, and the subsequent disposition of such units as may be desired.

In accordance with the invention of the 5 patent and application hereinabove referred to, the severance of the units and the stacking of the same rapidly in succession is a particular advantage, the paper of the sheets corresponding to the sheets 6 and 8 10 being so composed as to retard permeation of the same by moisture, thus permitting the sheets to be drawn or slid one over the other into stacked relation, after severance from the stock. Were the paper not so organized, 15 the units would become superficially moist and stick together and prevent such sliding action, so that such a cutter is particularly advantageous in use in accordance with the invention of said application and patent. 20 But we do not wish to be understood as in any sense acquiescing in a limiting or confining of the present invention to applicability to the inventions of said other application and of said patent, the invention being 25 likewise susceptible to many changes in provision, construction, formation, combination, association and relative arrangement of parts, members and features, in adapting the present invention to varying 30 conditions of use and service, and within a fair interpretation of the invention.

Having thus disclosed our invention, we claim and desire to secure by Letters Patent:

35 1. In apparatus of the character disclosed, a moving conveyer, and a cutter adapted to be applied to the conveyer during the movement thereof and to move with the conveyer during cutting action upon material advanced by the conveyer.

40 2. In apparatus of the character disclosed, a moving conveyer, and a cutter adapted to be applied to the conveyer during the movement thereof and to move with the conveyer during cutting action upon material advanced by the conveyer; said cutter being operated in the cutting action in a direction away from the conveyer surface.

45 3. In apparatus of the character disclosed, a moving conveyer, and a cutter adapted to be passed between the conveyer and material thereon whereby the cutter may be operated in the cutting action during the movement of the conveyer and in a direction away from the surface of the conveyer.

50 4. In apparatus of the character disclosed, a moving conveyer, and a cutter adapted to be passed between the conveyer and material thereon whereby the cutter may be operated in the cutting action during the movement of the conveyer and in a direction away from the surface of the con-

veyer; said cutter comprising a body and a flexible cutting element connected at one end 65 with the body.

5. In apparatus of the character disclosed, a moving conveyer, and a cutter adapted to be passed between the conveyer and material thereon whereby the cutter 70 may be operated in the cutting action during the movement of the conveyer and in a direction away from the surface of the conveyer; said cutter comprising a body and a flexible cutting element connected at one 75 end with the body, said body and said cutting element being provided with handles for joint insertion between the material and the conveyer and for relative movement in the cutting action. 80

6. In apparatus of the character disclosed, a moving conveyer, and a cutter adapted to be passed between the conveyer and material thereon whereby the cutter may be operated in the cutting action during 85 the movement of the conveyer and in a direction away from the surface of the conveyer; said cutter comprising a body and a flexible cutting element connected at one end with the body, said body and said cutting element being provided with handles for joint insertion between the material and the conveyer and for relative movement in the cutting action and said cutter being 90 elongated and provided with a reduced end 95 portion at which said cutting element is connected with the body.

7. A cutter for use with apparatus of the character disclosed, comprising an elongated body and a flexible cutting element connected at one end only adjacent to one end of said body. 100

8. A cutter for use with apparatus of the character disclosed, comprising an elongated body and a flexible cutting element connected at one end adjacent to one end of said body, said body and said cutting element being provided with handles. 105

9. A cutter for use with apparatus of the character disclosed, comprising an elongated body and a flexible cutting element connected at one end adjacent to one end of said body, said body and said cutting element being provided with handles and said body being provided with a reduced end portion 110 115 at which said cutting element is connected with the body.

In testimony whereof, we have signed our names to this specification in the presence of two subscribing witnesses.
